UNITED STATES PATENT OFFICE.

THOMAS H. SYMINGTON, OF BALTIMORE, MARYLAND.

DRAFT-GEAR.

1,115,747.

Specification of Letters Patent.

Patented Nov. 3, 1914.

Application filed April 4, 1912. Serial No. 688,456.

To all whom it may concern:

Be it known that I, THOMAS H. SYMINGTON, a citizen of the United States of America, residing at the city of Baltimore, State 5 of Maryland, have invented certain new and useful Improvements in Draft-Gear, of which the following is a specification.

The draft gear of my invention comprises a draw-bar, a yoke secured thereto and 10 mounted between the sills, a front stop, a rear follower extending substantially from sill to sill and notched to receive the arms of the yoke, shock-absorbing means between the front stop and the rear follower, a rear 15 stop in the form of an abutment on each sill, the follower engaging the abutments at points immediately adjacent the sills during buffing.

In the preferred form of my invention the 20 draft beams are provided with two sets of aligned, elongated slots. The horizontal yoke is correspondingly slotted, and the draw-bar is slotted in alignment with the slots of the front set in the beams and yoke. A 25 key is seated in each set of slots, the rear key serving as a forward stop. Any preferred form of shock-absorbing means is mounted within the yoke and serves to transmit to the sills, by way of the front 30 stop, the drawing stress applied by the draft gear. There is an abutment secured to each sill acting as a rear stop, and a rear follower, in the form of an H-shaped member, is mounted within the yoke, the arms of the 35 yoke passing through the notches or slots of the H and engaging the cross bar of the H. This follower serves to transmit buffing stress applied to the gear, from the shock-absorbing member to the sills by way of the 40 rear abutment, the extremities of the arms of the H bearing on the shoulders adjacent the sills, so that there is practically no bending moment applied to the sills, the stress being entirely one of compression and shear- 45 ing.

In the accompanying drawing I have illustrated a draft gear embodying the principle of my invention in its preferred form.

Figure 1 is a plan divided on the longitudinal center line of the gear, one half being a top view, the other being a section on the line 1, 1 of Fig. 3. Fig. 2 is a central longitudinal section, certain of the parts being shown in elevation. Fig. 3 is a transverse vertical section on the line 3, 3 of Fig.

1. Fig. 4 is an elevation of the H-shaped follower. Fig. 5 shows a modified form of follower.

Between the longitudinal sills or draft arms 1 is a horizontal yoke 2. The sills and yoke, as shown, are pierced with two sets of aligned, elongated slots, indicated by reference characters as follows: the slots of the front set in the sills 4, the rear slots 5, the front slots in the yoke 6, and the rear slots 7 in the yoke 7. There is a front key 8 placed in the slots of the front set, and a rear key 9 placed in the slots of the rear set. The draw-bar 10 is slotted at 11 to fit the front key which passes therethrough, and the front key serves to transmit tension stress direct to the yoke. The slots 6 extend to the rear so that compression stress is never applied to the yoke, and the key is also adapted to bear at times against the front 75 face of the slot in the sill to transmit extreme tension direct from the draw-bar to the sill when maximum drawing stress is applied, or to take a continued bearing thereagainst during drawing to prevent pulling 80 out of the draw-bar when failure of the gear occurs.

Within the arms of the yoke, as seen in plan view, is any suitable shock-absorbing member as the springs 12. For the purpose 85 of receiving the compressive force of the springs in drawing and transmitting the same to the rear key 9, which acts as a front stop, and also for the purpose of applying compressive force to the springs in buffing, 90 I have provided a front follower 13 mounted on the rear key and slotted to receive the same. This follower may be of any suitable or usual type, and any means for applying and transmitting pressure at the forward 95 end of the springs may be substituted for it. Within the arms of the yoke I have also shown a rear follower 14. This follower extends substantially from sill to sill and takes its bearing during buffing on shoulders 15 100 secured to the sills, forming rear abutments. The rear follower 14 is preferably an H-shaped member, see Fig. 3, the legs 16 of the H forming top and bottom arms of the follower, the extremities of which bear, during 105 buffing, on the shoulders 15 at points adjacent the sills. The rear arm 17 of the yoke bears on the central portion or connecting member of the H, indicated by 17', during drawing, and the notches 18 between the 110

legs of the **H** receive the arms of the yoke, and permit them to be suitably spaced from the sills and thereby avoid the cheek plates and the key bearings, etc. adjacent the slots 4 and 5.

The operation of the gear will be clearly apparent from the description taken in connection with the accompanying drawing.

The gear is shown in the position which it will take when subjected to no stress. In drawing, the stress is transmitted from the draw-bar to the front key 8, hence to the yoke, by which it is applied to the rear follower. The rear follower compresses the springs or friction gear and transmits stress to the front follower which is mounted on the rear key 9, the latter serving as a forward abutment. It will be noted that in normal position this key rests against the front ends of the slots 5 in the draft beams. As drawing is continued and the gear is compressed, the front key moves forward toward the front ends of the slots 4 in the draft beam, and under extreme stress, both keys bear against the front ends of their slots and the stress is applied direct to the sills. If any portion of the gear fails, the front key forms a rigid connection between the draw-bar and sills. This prevents pulling out of the draw-bar. In buffing, stress is applied first by the draw-bar to the front follower 13, which transmits it through the shock-absorbing gear to the rear follower 14, by which it is transmitted from the extremities of the arms 16 of the **H**-shaped follower to the shoulders 15 at points closely adjacent the sills. By applying the stress at points closely adjacent to the central webs of the sills, the bending moment is substantially eliminated and consequent spreading of the sills is avoided. Under extreme buffing stress the keys take a bearing against

the rear ends of their slots and thus prevent destruction of the springs.

In Fig. 5 I have illustrated another form of follower having slots 20 instead of notches 17 to receive the arms of the yoke. Its operation will be easily understood in connection with the description. The edges 21 of this follower engage the rear stop immediately adjacent the sills in buffing as do the ends of the arms of the **H**-shaped follower.

I have thus described my invention in its preferred form in order that its nature and operation may be clearly understood. However, the specific terms herein are used in their descriptive rather than in their limiting sense.

What I claim and desire to secure by Letters Patent is:

In a draft gear having two keys only, a slotted draw-bar, a draft beam having front and rear sets of aligned slots, a horizontal yoke having corresponding slots, one key passing through the slot in the draw-bar and seated in the forward set of slots in the yoke and draft beams, the second or rear key passing through the rear slots in the yoke and draft beams and serving as a forward stop, a rear stop consisting of separate, independent abutments, one secured to each sill and a rear follower in the form of an **H**-shaped member, the connecting arm of the **H** being encircled by the yoke and the ends of the legs of the **H** bearing against the rear stop at points immediately adjacent the sills.

Signed by me at Baltimore, Maryland, this 2d day of April, 1912.

THOMAS H. SYMINGTON.
